UNITED STATES PATENT OFFICE.

JOSEPH E. MCKINNEY, OF MINNEAPOLIS, MINNESOTA.

ANTISLIPPING DEVICE.

1,403,799.

Specification of Letters Patent. Patented Jan. 17, 1922.

Application filed April 20, 1921. Serial No. 462,943.

To all whom it may concern:

Be it known that I, JOSEPH E. MCKINNEY, a citizen of the United States, residing at Minneapolis, in the county of Hennepin and State of Minnesota, have invented certain new and useful Improvements in Anti-Slipper Devices, of which the following is a specification, reference being had to the accompanying drawings.

10 This invention relates to certain improvements in anti-slipping devices, and it is an object of the invention to provide a novel and improved device of this general character which, when applied to the tread portion of a wheel, operates effectually to facilitate traction and also to prevent side skidding.

15 Another object of the invention is to provide a novel and improved device of this general character adapted to be transversely disposed across the tread of a wheel structure and embodying one or more walls or flanges, the contacting edge or edges of which are irregular with no two longitudinal adjacent points thereon lying in the same horizontal or vertical plane.

An additional object of the invention is to provide a novel and improved device of this general character adapted to be disposed transversely across the tread of a wheel structure and including a wall or flange formed with corrugations, the contacting edge of the wall or flange winding up and down and from side to side throughout the length of said wall or flange.

Furthermore, it is an object of the invention to provide a novel and improved device of this general character embodying a shoe adapted to be disposed transversely of the tread of a wheel structure and which shoe is irregular both as to width and as to the height of the same, thereby better enabling the shoe to grip more firmly the roadway or other surface and create a mesh therewith.

The invention consists in the details of construction and in the combination and arrangement of the several parts of my improved anti-slipping device whereby certain important advantages are attained and the device rendered simpler, less expensive and otherwise more convenient and advantageous for use, as will be hereinafter more fully set forth.

55 The novel features of my invention will hereinafter be definitely claimed.

In order that my invention may be the better understood, I will now proceed to describe the same with reference to the accompanying drawings, wherein:

Figure 1 is a fragmentary view in side elevation illustrating an anti-slipping structure constructed in accordance with an embodiment of my invention and in applied position;

Figure 2 is a view in perspective of one of the tread members or shoes as herein disclosed, unapplied;

Figure 3 is a view in front elevation of a tread member or shoe as herein disclosed, the connecting links being shown in fragment and the wheel structure being diagrammatically indicated by dotted lines;

Figure 4 is a view in top plan of a tread member or shoe as herein disclosed;

Figure 5 is a view in side elevation of a tread member or shoe constructed in accordance with a further embodiment of my invention;

Figure 6 is a view in plan of the shoe or member as disclosed in Figure 5; and

Figure 7 is a sectional view taken substantially on the line 7—7 of Figure 5.

As disclosed in the accompanying drawings, R denotes the rim of a wheel structure coacting in a conventional manner with a carcass C of an inflatable tire, although my improved device is not limited for use with this particular type of tire. Bridging or straddling the tread portion of the carcass C are the members or shoes M comprised in my improved anti-slipping device. The members or shoes M may be of any desired number in accordance with the requirements of practice and are maintained in desired spaced relation through the instrumentality of the side chains S, the opposite end portions of each of the members or shoes M being operatively connected with the side chains S by the links 1, preferably of the type shown in the accompanying drawings.

Each of the members or shoes M is rigid or non-flexible and comprises an elongated body longitudinally curved to conform closely to the cross sectional configuration of the tread portion of the carcass C when under load. The opposite ends of the body portion 2 of each of the members or shoes M are provided with outstanding eye members 3 having their inner peripheral portions substantially in continuity with the inner or under face of the member or shoe M.

A link 1 is operatively engaged with each of the eye members 3 and as said eye members extend outwardly beyond the adjacent end of the member or shoe M, a greater leverage is provided to hold each end portion of the member or shoe more rigidly to the carcass C whenever the wheel structure has a tendency to side skid and, therefore, prevent the member or shoe M from turning 10 around so far that the weight of the vehicle no longer rests on the shoe or member M and which would otherwise occur in the event the side chains S are loosely connected or hooked together.

15 The side or longitudinal margins of the body portion 2 of each of the shoes or members M are defined by outstanding flanges or walls 4 arranged in slight convergence toward the body portion 2 and whereby said 20 member or shoe M is substantially U-shaped in cross section. Each of the flanges or walls 4 is provided with the corrugations 5 extending transversely of said wall or flange and substantially at right angles to the body 25 portion 2.

The outer marginal portion of each of the walls or flanges 4 or more particularly the outer marginal portions of alternate corrugations are recessed, as at 6, so that each of 30 the flanges or walls 4 has an undulated or serrated contacting edge, the points *a* and *b* in said edge forming an irregular curve winding up and down and from side to side throughout the length of said wall, no two 35 longitudinal adjacent points *a* and *b* lying in the same horizontal or vertical plane when a member or shoe M is in contact with a roadway or other surface. It is also to be noted that the outer or high points *a* of each 40 of the walls or flanges 4 are substantially coplanar.

The particular formation or construction of the flanges or walls 4, as hereinbefore set forth, is of decided advantage as such flanges 45 or walls provide a recurring and substantial resistance to the surface with which they come in contact and more especially when coming into contact with a car track, the edge of a paving block or other protuberance 50 in a roadway or other surface.

Each of the side chains S is provided on one end with a fastening member F adapted for detachable engagement with the opposite end portion of the chain so that the complete 55 anti-slipping structure may be readily and conveniently applied to a wheel.

In the embodiment of my invention as illustrated in Figures 5 to 7, I disclose a shoe or member S' wherein the body portion 60 2' is provided with a central outstanding wall or flange 4' positioned at substantially the transverse center of said body portion 2' and substantially coextensive in length with the length of the body portion 2'. This wall

or flange 4' is substantially of the same form 65 and construction as the wall or flange 4 hereinbefore referred to.

From the foregoing description it is thought to be obvious that an anti-slipping device constructed in accordance with my 70 invention is particularly well adapted for use by reason of the convenience and facility with which it may be assembled and operated, and it will also be obvious that my invention is susceptible of some change and 75 modification without departing from the principles and spirit thereof and for this reason I do not wish to be understood as limiting myself to the precise arrangement and formation of the several parts herein 80 shown in carrying out my invention in practice except as hereinafter claimed.

I claim:

1. An anti-slipping device for tires including a member adapted to straddle the 85 tread portion of the tire, said member including an outstanding corrugated wall having an undulated contacting edge, the points in said edge forming an irregular curve winding up and down and from side to side 90 throughout the length of said wall.

2. An anti-slipping device for tires including a member adapted to straddle the tread portion of the tire, said member including an outstanding wall, the outer margin of the wall being serrated, said wall presenting an irregular contacting edge, no two longitudinal adjacent points thereon lying in the same horizontal or vertical 95 planes.

3. An anti-slipping device for tires including a body member adapted to straddle the tread portion of the tire, said member including an outstanding wall formed with corrugations extending substantially at right 100 angles with respect to said body member, the turns in said wall extending in the same direction and being notched at their outer marginal portions to form an irregular contacting edge winding up and down and from 105 side to side throughout the length of said wall.

4. An anti-slipping device for tires including a body member adapted to straddle the tread portion of the tire, said member including an outstanding wall formed with corrugations extending substantially at right angles with respect to said body member, the turns in said wall extending in the same direction and being notched at their outer 110 marginal portions to form an irregular contacting edge winding up and down and from side to side throughout the length of said wall, the outer points of the wall being substantially coplanar.

In testimony whereof I hereunto affix my signature.

JOSEPH E. MCKINNEY.
